(57) **CLAIM**

The ornamental design for a control for musical equipment, as shown and described.

DESCRIPTION

FIG. 1 is a left, front perspective view of a control for musical equipment showing my new design wherein elements shown in phantom lines are not a part of the claimed design.

FIG. 2 is a left side elevational view thereof, the right side elevational view being a mirror image thereof.

FIG. 3 is a rear elevational view thereof.

FIG. 4 is a front elevational view thereof; and,

FIG. 5 is a bottom plan view thereof.

The broken lines shown around the knob are for illustrative purposes only and form no part of the claimed design.
